HOLDER FOR HAIR CUTTER OR THE LIKE

Abraham N. Spanel, Princeton, N. J.

Application July 5, 1951, Serial No. 15,770

Term of patent 14 years

(Cl. D58—12)

To all whom it may concern:

Be it known that I, Abraham N. Spanel, a citizen of the United States and a resident of Princeton, in the county of Mercer and State of New Jersey, have invented a new, original, and ornamental Design for a Holder for Hair Cutter or the like, of which the following is a specification, reference being had to the accompanying drawing, forming part thereof, wherein:

Fig. 1 is a top plan view of a holder for hair cutter or the like embodying my new design;

Fig. 2 is a side elevational view of the holder for hair cutter or the like shown in Fig. 1;

Fig. 3 is a bottom plan view of the holder for hair cutter or the like shown in Figs. 1 and 2; and

Figs. 4 and 5 respectively are front and rear end views of the holder for hair cutter or the like shown in Figs. 1, 2 and 3.

I claim:

The ornamental design for a holder for hair cutter or the like, substantially as shown.

ABRAHAM N. SPANEL.
